United States Patent Office.

CLARK T. BUSH, OF MIDDLEBURG, NEW YORK.

Letters Patent No. 92,579, dated July 13, 1869.

IMPROVEMENT IN IRON FENCE.

The Schedule referred to in these Letters Patent and making part of the same.

To all whom it may concern:

Be it known that I, CLARK T. BUSH, of Middleburg, in the county of Schoharie, and State of New York, have invented certain new and useful Improvements in Iron Fences; and I do hereby declare that the following is a full, clear, and exact description of the construction of the same, reference being had to the accompanying drawings, in which—

Figure 1 is a perspective view;

Figure 2 shows the manner of splicing;

Figure 3, the manner of bracing the posts; and

Figure 4, a top view of the post and link.

Similar letters of reference indicate corresponding parts in the several figures.

The object of this invention is to construct a strong and durable fence, in such a manner as to avoid the expense of mortising or drilling the rails or pickets, and to enable the builder to put it together or take it apart with great facility.

In the drawings—

H represents the foundation, in which are secured the posts A A.

P P are the pickets or palings, attached to the rails r r by hooks or eyes a a, which may be cast upon the back side of the pickets. These pickets may be of any form, to suit the taste of the builder.

The rails r r are fastened near the top and bottom of the post, as shown in fig. 1, by means of the metallic links L L, the post being notched as shown at e in fig. 3, to receive the rail, and prevent its moving up or down.

The links may be made of wrought or malleable metal, bent in the form shown.

The rails r r being made in sections, are jointed together by a metallic band, B, and key k, the ends being spliced, as shown in fig. 2.

The splice may be made at the post, and the link be made to serve the same purpose that the band does, the key being placed in the middle of the splice, the same as when the band is used.

The posts A A may be effectually braced, as shown at fig. 3. Where b is the brace, the upper end of which rests against the post and is secured by the band w and the pin or key t.

From the above description it will be seen that this fence is simple in construction, can be cheaply built, and is strong and durable.

I do not claim constructing a metallic fence with movable pickets, having the rails pass through eyes or hooks attached to said pickets; but

What I do claim as new, and desire to secure by Letters Patent, is—

1. The combination and arrangement of post A, (provided with recess,) rails r r, and metal links L L, as shown and described.

2. The kerfed rails r r, band B, and key k, when said several parts are arranged as shown and specified.

3. The combination and arrangement of the herein-described posts A A, rails r r, pickets P P, and braces b, substantially as described.

C. T. BUSH.
